UNITED STATES PATENT OFFICE

2,509,001

AQUATIC DEVICE

John G. Johnson, Tacoma, Wash.

Application November 15, 1946, Serial No. 710,179

1 Claim. (Cl. 9—18)

1 This invention relates to water amusement devices and has reference more particularly to a novel form of water carrier, or vehicle, in the nature of a float and in which one or more persons may sit, partially submerged in the water, and manually propel the vehicle for amusement and transportation.

It is the principal object of this invention to provide a device which is to some extent, an improvement upon the water vehicle described in my U. S. Patent No. 2,139,022, issued on December 6, 1938, particularly in the design of floats or supports for the device, that makes the device more buoyant and stable, and the type of support or carrier for the person using the device.

It is also an object of this invention to provide a support or chair for the occupant that may be adjusted to different positions of inclination and also upwardly or downwardly relative to the float in order that the occupant may be placed to more or less extent in the water.

Still other objects of the invention reside in the details of construction of parts of the device in their relationship and mode of use as will hereinafter be fully described.

In accomplishing the above mentioned and other objects of the invention, I have provided the improved details of construction, the preferred forms of which are illustrated in the accompanying drawings wherein:

Fig. 1 is a plan view of a water vehicle embodying the novel features of my invention therein.

Fig. 2 is a side view of the same.

Fig. 3 is a front end view of the vehicle, indicating its normal position in the water.

Fig. 4 is a side view of a tandem vehicle of modified form.

Referring more in detail to the drawings:

In its present preferred form of construction, the device comprises two spaced, parallel pontoons 1 and 2 of substantial length and size and having the necessary buoyancy for the intended use of the device. Preferably, the pontoons are made of balsa wood, to give lightness to the structure without detriment to buoyancy, and as used by the ordinary person, these pontoons would be about eight feet long, three inches wide and eight inches deep.

The two pontoons, or runners, are tapered at their forward ends as shown in Fig. 1 and they are joined across their rearward end portions and held rigidly in spaced relationship as shown in Fig. 1, by a wooden deck plate 3 preferably comprising a sheet of ply-wood that has its opposite

side portions overlying and bolted to the top surface of the pontoons. This plate covers approximately the rear third of the space between the pontoons.

5 The longitudinal edges, and the rear edge of the deck piece 3, are covered and reinforced by wooden angle strips 5 applied thereover as shown in Fig. 1 and secured by bolts or screws applied therethrough and into the pontoons.

10 Extended between the pontoons at the forward edge of the deck piece 3, is a rigidly mounted frame structure comprising a bottom cross bar 10 that is fixed at its opposite ends to the pontoon and also is fixed to the forward edge of the deck piece. Fixed to and extended upwardly from the opposite end portions of the cross bar 10 and slightly rearwardly inclined are flat, board standards 11—11, joined across their upper ends by a cross bar 12. Brace bars 13—13

15 are fixed to the upper-end portions of these standards and to the deck plate 3 as shown in Figs. 1 and 2 to brace and hold the frame structure rigid relative to the pontoons. Suspended between the pontoons and from the frame structure just de-

20 scribed, is a chair or seat on which the person using the device may sit partially submerged in the water. The chair includes a back portion and a seat portion. The back portion comprises a plurality of wooden cross slats 20 that are fixed

25 at their opposite ends to upright rails 21—21 that engage in sliding contact with the front surfaces of the corresponding standards 11—11. The seat portion comprises the opposite side rails 22—22 on which cross slats 23 are fixed to form **30** the seat. The side rails extend substantially forward from the seat and have the opposite ends of a cross strap 24 fixed thereto on which the user may rest his legs if he so desires.

35 The rails 22—22 have their rear end portions pivotally attached by bolts 25 to the lower ends of the back rails 21—21 and their forward portions are adjustably supported by rods 26 which are attached thereto and to the side rails of the back. These rods include turn buckles 27 **40** therein which provide for lengthening or shortening the rods thus to change the angular relationship of the bottom or seat portion and the back portion.

The chair as so constructed is adjustably suspended from the top cross bar 12 of the back frame by a rod 30 which, at its upper end is rotatably passed through a hole in the cross bar 12 and held by a wing nut 31 fixed on its upper end. Along its lower end portion, the rod 30 is threaded as at 32 and passes through a nut 35

that is fixed to one of the lower cross slats of the back portion of the chair. By turning the wing nut 31 in one direction or the other, the chair may be adjusted upwardly or downwardly relative to the pontoons and in this way the user may be raised or lowered in the water.

For propelling the device in water, I have provided a pair of paddle wheels 40 located at opposite sides and forwardly of the chair. Each paddle wheel has its mounting shaft 41 revolvably carried in bearings 42 of a rectangular frame 43 carried in upon the corresponding pontoon. The lower portions of the paddle wheels extend into the water. Fixed at the inner ends of the paddle wheel mounting shafts, are hand cranks 45—45 and these are easily accessible to the person using the device when sitting in the chair. By means of the two cranks, the paddle wheels may be rotated to propel the device forwardly, rearwardly or to make turns in the water. The frames 43 are adjustably secured upon the beams 1 and 2 and may be moved forwardly or rearwardly to best suit the user. It is shown in Figs. 1 and 2, that bolts 47 are fixed in the beams and extend through longitudinal slots 48 in longitudinal frame members to provide for the adjustment.

Assuming the device to be so constructed, it will be understood that in using it, the user merely sits in the chair portion, reaches forward, grasps the cranks of the paddle wheels and turns them in unison to propel the device forwardly or rearwardly or turn them unequally or in opposite directions for making turns.

The adjustability of the seat permits the user to be raised or lowered in the water to suit his desires and the chair seat may be adjusted to give a desired inclination.

In Fig. 4 I have illustrated a similar device of tandem arrangement. This employs pontoons like those of the device already described and is equipped with a forward and rearward seat structure, each like that already described. This device however, is with a different type of propelling mechanism.

In this structure, bearings 50 are fixed to the forward cross slat of each of the seats and extending rotatably through the bearings are tubular shafts 52 adapted for rotation within certain limits. At their upper ends, the shafts 52 mount paired hand cranks 53—53 thereon and

at their lower, rearwardly extended ends, each mounts a propeller 54; it being shown that the lower end portion of each tube is curved rearwardly to substantially horizontal position. A flexible shaft connects the hand cranks of each shaft with the propeller for its operations. In this device, two people are to be accommodated to cooperate in the propulsion and steering of the craft.

10 Devices of the kinds described may be made in various sizes and proportions, and details of construction might be changed without departing from the spirit of the invention.

Having thus described my invention, what I claim as new therein and desire to secure by Letters Patent is:

An aquatic device of the character described, comprising a float having opposite side members, a deck plate rigidly joining said members across their rearward end portions, a transverse, upright frame structure fixed to said deck plate adjacent its forward edge, a seat frame comprising a back portion disposed against the forward side of the upright structure and extending downwardly therefrom, a seat portion pivotally attached to said back portion for the support of an occupant partially submerged in the water, tie rods supporting the seat portion from the back portion and of adjustable length to determine the inclination of the seat portion, and a hanger rod attached to said back frame portion and adjustably fixed in the said upright frame structure for determining the position of the said seat frame, and propulsion means positioned for manual operation by an occupant of the seat.

JOHN G. JOHNSON.
